UNITED STATES PATENT OFFICE.

HENRY A. NICHOLSON, OF ARKLES BAY, AUCKLAND, NEW ZEALAND, ASSIGNOR TO
ERNEST A. CRAIG, OF AUCKLAND, NEW ZEALAND.

STEAM GENERATOR.

Application filed June 24, 1919. Serial No. 306,398.

This invention relates to steam-generators; being directed partly to the type of generator disclosed in my pending application No. 284,657, filed March 24, 1919, and 5 partly to improvements in means for generating steam by the combustion of oil, both in the type of generator set forth in said application and also in other types of generators and boilers, etc.

10 In said application is disclosed a non-circulatory generator in the nature of a water pipe or main, into one end of which water is forced under high pressure by a pump, and at the other end of which the 15 water is converted and delivered as steam or as steam and water, having been heated constantly while advancing only once and in the same direction through said main; the delivery being into a steam- 20 drum mounted in the furnace uptake, whereby the residuum (if any) of water is converted into steam. The main is also shown as divided at one portion into a grid, by which the stream is split up into fine di- 25 visions for more intimate exposure to the heat; a suitable water drum being also included in said main, for providing a reserve body of highly heated fluid under high pressure. At the terminal of the water main or 30 system, the fluid is delivered in the form of steam, or a mixture of water and steam, through a converting device.

There is illustrated in the present drawings a method of generating steam by means 35 of a single-direction water-flow main or system, by the use of oil as a fuel. The fuel is shown as consumed in a flame chamber beneath a water grid, but preferably separated therefrom by a bridge; and the water main 40 preferably includes a coil imbedded in said bridge, to be subjected to heat both above and below. There is also shown imbedded in the front wall of the grid chamber, a vertical coil consisting of a zigzag section of 45 the fluid main, through which the fluid courses from top to bottom, so that it receives the greatest heat as it reaches the bottom; and preferably from this point the fluid courses to and fro around three sides 50 of the flame chamber, in a zigzag course, before entering the water-reserve-drums. Two of these drums are provided to augment the capacity of the system and increase the safe- 55 guard against trouble.

The oil-burner, of which as many may be

employed as required, four being illustrated, embodies a substantial departure from the prevailing method of injecting oil into the combustion-chamber in a boiler in the form of a sheet or spray of oil, forcing a powerful air blast through the flame chamber in an attempt to burn the oil as rapidly as possible, and resulting in the loss of many heat units through the escape of unconsumed fuel through the smoke pipe. An object of 60 certain of the present improvements is to provide for an increase in the length of the life of the flame, or, in other words, to extend the time used for combustion of each atom of the fuel, so that it will be fully consumed while coursing through the generator. I aim to produce a rolling flame or flame cloud, which will float at moderate speed through the flame chamber and up around the grid, to deliver a maximum of heat to 65 the water. At the burner I force into the furnace a constant stream of air from a pump or blower, this stream having great volume but relatively low rate of flow; and it enters the furnace through an inlet that 70 flares on its inner or furnace side, with the effect that a large volume of air is supplied at relatively low speed. Into this air stream, at the point where the inlet begins to flare, the fuel oil is fed under pressure through a 75 spreader or spray having the effect of atomizing the oil. To do this, the oil is caused to escape from a jet which has a flaring mouth, said mouth being closed by a conical plug, which is held closed by a spring. The 80 force of the feed oil will overcome the power of the spring, and a minute opening will be formed, that is, the cone plug will separate very slightly from the flaring mouth of the jet, making only space enough for the oil to 85 escape in an extremely fine or atomized condition, into the inflowing stream of air, at the place of highest pressure of the latter. From this point of oil supply, the air begins to expand in volume, as well as to advance at lower speed, and the air and fuel mix to form a mist or cloud, adapted to float slowly through the flame chamber and up through the water-tube grid. The fine atomizing of the fuel in this air supply insures 90 its perfect combustion, and the progress of the mixture through the furnace is sufficiently slow to afford time for the completion of the combustion. Hence a substantially larger number of heat units is utilized 95 100 105 110

from the fuel than has heretofore been found practicable.

Other features and advantages will hereinafter appear.

5 In the accompanying drawings,

Figure 1 is a sectional elevation taken from front to rear of an oil-burning steam-generator embodying the present improvements in one form.

10 Figure 2 is an enlarged sectional detail of the oil and air feed to the furnace.

Figure 3 is a plan of the generator.

Figure 4 is a sectional rear elevation of the generator, to show the zigzagging portion of the main at the front of the grid chamber, as well as the zigzag box portion 15 of the main surrounding the flame chamber, and in the bridge over the flame chamber or furnace. This also shows the nozzles of the 20 four fuel burners.

Figure 5 is a front sectional elevation, showing a section of the water grid, and also illustrating a part of the zigzag box course of the water main around the furnace.

25 Figure 6 is a sectional plan showing the zigzag course of the main through the bridge over the furnace, and also indicating by dotted lines the boxed zigzag portion of the main around the furnace.

30 Figure 7 is a diagram of the water main and subdivisions and appurtenances.

Figure 8 shows the preferred manner of connecting the fire-box bridge-coil in the system.

35 A force pump 10 is connected to one end of a main which is designated generally as 11, and which comprises a riser 12, connected by an elbow 13 and a backcheck valve 14 to the uppermost of a set of horizontal pipes 15

40 of the same diameter as the main 11, and forming a vertically arranged coil or zigzag section of the main, these pipes being preferably cast in one piece and connected at alternate ends by unions in the form of U-shaped 105 fittings 16, Figure 4, said fittings being retained by straps and nuts 17, which permit of easy removal of the couplings for inspection, cleaning and replacement.

45 This zigzag set of pipes is embedded in the front wall 18 of the generator, which is heated by the flames and gases rising from the furnace or flame chamber 19, so as to give a preliminary heating to the water as it is forced through the generator by the 50 pump 10.

55 The lowermost of the couplings 16 is a special fitting, being connected by an elbow 20, Figures 4 and 6, to the first or right-hand one of a set of horizontal pipes 21 overlying the flame chamber or furnace 19, and embedded in a bridge 22 of bricks, blocks or plates of refractory material, which extends from the front wall of the flame chamber nearly to the back wall thereof, leaving an 60 opening 23 for the egress of flames and gases

at the back of the flame-chamber. These pipes are connected to form a horizontal zigzag course by means of unions or couplings 24 cast in front and rear horizontal headers 25 and 26, also embedded in the 70 material of the bridge, the front header having clean-out openings for all the pipes in the set, these openings closed by screw plugs 37. Before passing into the reserve drums presently to be described, the water receives 75 a high degree of heat from its passage through this bridge coil.

After traversing said bridge coil, the fluid is led to and fro around the sides and back of the flame-chamber, for further heating. The connection between the bridge coil and the fire-box coil is in the form of an inclined U-fitting 28, Figures 4 and 6. This joins with the topmost pipe 29 in a set at the side of the fire-box. Pipe 29 is joined 80 by an elbow 30, Figure 6, to the topmost pipe in a set 31 at the rear of the fire-box, the latter communicating by an elbow 32 to the top pipe in a tier 33 at the right-hand side of the box. At the front end of this topmost pipe 33, it is connected by a U-connection 34 to the next underlying pipe in set 33, which by means of elbows communicates 85 with corresponding pipes in the rear and left-hand sets 31, 29. Some of these elbow 90 and U-joints may be formed in headers 35, 36 placed at the rear corners of the fire-box and partly or wholly encased in the walls thereof. In the front may be fitted clean-out screw plugs 37, Figure 1, and in the rear 95 headers may be similar plugs 38, Figure 6; one of the features of the invention being the provision of facilities for readily cleaning out pipes and tubes that are arranged to 100 perform the described functions. It will be 105 seen that after zigzagging through the bridge coil, the fluid zigzags through the three-section fire-box coil, and receives additional heat, without, however, having the effect of unduly cooling or shortening the flames, 110 since the material of the fire-box walls and the bridge may be refractory and heat-conducting, and adapted to become incandescent, to present a highly heated surface to the 115 flames, while heating the embedded coils. It will be noted that the two middle pipes of the set of four in the left-hand side wall (or the right-hand at Figure 4, which is a rear view) may be joined by a U-passage 39 provided in the header at this corner.

120 From the lowermost pipe in the right-hand section 33 of the fire-box coil, the fluid (which has been gradually heated and finally brought to a high degree of heat at the hottest part of the generator) is led out through a pipe 40, elbow 41 and riser 42, Figures 3, 4, 6, the upper end whereof is connected to horizontal pipe 43, Figure 3, leading by elbows 44 and 45 to a hot water reserve drum 46, mounted horizontally in the top of the 125

generator, to be heated by the escaping gases; this being the middle of the three drums shown. For additional safeguard there is preferably employed a second reserve water drum 47, in front of the first; all three drums mounted upon bridgework 48 at the top of the generator, Figure 1, and beneath a dome 49, passages being left for free circulation of hot gases all around the drums as they rise to the smoke pipe 50 erected upon the middle of the dome.

Said reserve water drum 46 is directly connected to said auxiliary reserve drum 47, the fluid flowing from the upper part of the first through a diagonal connection 51 to the lower part of the auxiliary drum 47, the latter having in the upper portions of its ends outlets 52. These outlets are in the upper portions of the drums, to insure against the collection of steam in the latter. If steam should form in either drum, it would rise to the top, and so be forced out of the drum ahead of the water. Hence there is maintained a large reserve of water 25 heated above the boiling point.

From the ends of the auxiliary reserve drum 47 the heated fluid is led through the fittings 52 and elbows 53 down through vertical pipes 54 to join the forward ends of 30 distributing headers 55, 56, one at either side of the combustion chamber. These headers open into vertical grid sections or coils, each comprising opposite vertical side headers 57 and 58, and each also comprising a vertical 35 series of horizontal tubes 59 opening into said side headers, the latter having therein suitable U-connections 59^a, so that each section is a zigzag coil through which the fluid advances down from the distributing header 40 on one side to the collecting header on the opposite side, there being two of these collecting headers 60 and 61. Each grid section or coil is detachable from the generator, and provided with clean-out openings 45 having plugs 62, and having flanged connections 63 at diagonally opposite corners with the headers, and adjustable supports 64 at the remaining two corners, all as set forth in my said application. By these small tube coils is formed a grid, up through which course the flames and hot gases to the top of the generator, the fluid being divided up by the tubes into small streams, to expose it more intimately to the flames and gases. 50 The final heating of the fluid occurs at the lowest portion of the grid, nearest to the fire box, where the generator is hottest; and at this stage the fluid is heated very far above 212 degrees, and is under high pressure.

From the collecting headers 60, 61 the fluid, heated to a high temperature, advances through elbows 65, risers 66 and elbows 67 to forwardly-extending horizontal pipes 68, 65 in which are provided pressure-reducing jets

69 and 70, opening into the ends of a steam drum 71 placed in rear of the water reserve drums. By these jets or valves 69, 70, which are of small diameter in comparison with the main pipes 67 and 68, the pressure in 70 the fluid main is kept above the pressure in the steam drum.

From an outlet 72 at the top of the steam drum leads a service pipe 73 provided with a stop valve 74, and also an elbow 75 carrying a service safety valve 76. A second safety valve 77, set at say 100 pounds higher pressure than valve 76, may be provided at the top of the auxiliary water reserve drum 47. Under ordinary conditions, the pressure in the generator will not get above the point at which the service safety valve 76 is set; but if the emergency valve 77 should blow off while the service valve 76 remains closed, the attendant will be warned thereby 80 that fluid is not flowing freely through the grid, or that some other trouble has developed.

While the generator is being warmed up, the pump 10 is still, but there is a certain 90 circulation of water in the main, including the grid, which prevents overheating of the tubes or main at any point. This circulation is automatic, being due to the heating of the water, which as it gets warm rises to 95 the top of the generator, and then as it cools descends to the bottom, to become re-heated and rise again. To secure this flow of water while warming up the generator, valves 78 and 79 are opened in pipes 80 and 81, to 100 open communication between the steam drum (which may now be nearly filled with water) and the water reserve drum 46. Valves 82 and 82^a in pipe 83 are also opened, to effect direct communication between reserve water 105 drum 46 and the standing coil 15 at the front of the combustion chamber, the fluid passing down said coil 15 and thence to the bridge coil 21 and the fire-box coil 29, 31, 33. A valve 84 may also be opened, to open up 110 a free communication between the auxiliary reserve drum 47 through pipe 43 to main 42. As the water warms, it will rise through the grid and flow through the upper headers and pipes to the drums, and will descend 115 through the risers to the bottom of the grid, in which it will rise again to the drums, thus maintaining the circulation.

In this way the water will continue to heat and circulate until steam is present in 120 the steam drum, whereupon the force pump may be started, and valves 78, 79, 82, 82^a and 84 closed, so that the direction of flow of the fluid will be reversed, and take the course through the pre-heating coils, the 125 water-reserve drums, the grid, and to the steam drum, as disclosed in the earlier portion of this description. The steam-drum is also heated by the hot gases rising through the generator to the uptake, whereby there 130

is converted into steam any residuum of water that may enter the steam-drum.

Preferably the bridge-coil 21 should be included in the main between the grid and the steam drum, Figure 8, so that the fluid 5 may be exposed to the greatest heat just as it is about to be delivered to the steam drum. For this purpose the two bottom or collecting headers may be connected by a cross pipe 10, from which may lead a pipe 86 comprising elbows or fittings 87 and 88, to one 15 end of the bridge-coil, at 89; a pipe 90 leading from the other end of the bridge-coil and being connected through elbows or fittings 91 and 92 to a cross main 93, which, at its ends may be connected by risers 66 to the elbows 67 leading to the steam drum. The lower end of the vertical front coil may be connected directly by a duct or fitting 20 95 to the upper end of one side of the box coil.

Into the front of the fire-box 19 may open four burners 100, one of which will be described in detail. The fuel oil is forced by a 25 pump 101 into a cross main 102, from which branches 103 extend to the burners 100, each branch terminating in a diagonal pipe 104, Figure 1, or an elbow 105, Figure 2, opening into a chamber 106 having an outlet 107 of 30 small diameter and flaring outwardly; this outlet being formed at the apex of a conical shell 108 located at the outer end of an orifice 109 in the front wall of the fire-box. The oil is forced through the outlet 107 and 35 through said opening 109 into the fire-box or flame-chamber 19. Said outlet 107 is normally closed by means of a plug 110, which may be of conical form to fit the flaring outlet, and may be provided with a guiding stem 40 111, fitting in a guide-hole 112 in a burner plate 113 arranged vertically upon the front wall of the furnace and containing the oil inlet 105. This stem may be prolonged and surrounded by a compression spring 45 114, which is compressed between a head 115, carried upon the outer end of the stem, and the plate 113. The spring holds the outlet closed until its resistance is overcome by the pressure of the oil as it is forced by 50 the pump 101; this oil pressure sufficing to make a minute opening between the plug 110 and the mouth 107 of the burner, permitting the oil to escape in the form of a conical sheet or spray in atomized condition; the opening in the front wall of the 55 furnace flaring inwardly at 116 to permit this spraying of the oil without striking the furnace wall edges, and to favor the formation of a slowly advancing flame cloud.

60 As the oil emerges in this atomized condition, it mixes with a current of air derived from a blower 117, which communicates with one end of an air box 118 at the front of the fire box, said air box extending 65 the width of the furnace, and having

four openings 109 into the fire box, one for each burner. The air is under pressure of say half a pound from the blower or pump, and mixes with the spraying atomized sheet of fuel, forming a fog, which is not rushed 70 hastily through the fire box, but is advanced at relatively low speed, to give the fuel ample time for combustion; the flow of the current being controllable partly by a damper 119 in the vent pipe or stack 50, Figure 1. 75 The oil is discharged into the air current where the pressure of the latter is greatest, and from this point the air, entering through the flaring orifice 116, is reduced somewhat in pressure; and the mixed air 80 and fuel burn in a rolling flame, the time of combustion being prolonged, and the flame passing back through the fire box and up through opening 120 in the top, back of the bridge, and up through the grid. 85

Within the grid chamber may be arranged baffle plates 121 to prolong the course of the flame and gas through the chamber, and afford more opportunity for the fluid to take up the heat; these baffle plates being placed 90 between alternate rows of grid tubes, and being arranged so as to leave flame and gas openings or passages at the front and back of the grid chamber alternately, so that the flames pursue a zigzag course. 95

Variations may be resorted to within the scope of the invention, and portions of the improvements may be used without others.

Having thus described my invention, I claim:

1. A steam generating apparatus comprising a combustion chamber with a continuous coil of large diameter extending around the sides thereof, a bridge above the chamber with a large coil extending back and forth therethrough and connected at one end with the combustion chamber coil, coils of pipe of smaller diameter extending downwardly and terminating just above the bridge, a water drum between the large and small coils and a steam drum into which the smaller coils deliver, said coils being all connected at their entrance ends with the large combustion chamber and bridge coils, and means to force fluid only once first 105 through the large coils, and thence through the small coils into the steam drum. 110

2. In a steam generating apparatus, a combustion chamber, a bridge extending over the top from the front to nearly the back of the combustion chamber, a preheating zig-zag coil embedded in the bridge, a heating chamber above the combustion chamber, a pre-heating ziz-zag coil in front of the heating chamber and in communication with the coil in the bridge, a series of smaller coils in the heating chamber, a water drum and a header interposed between the preheating coils and the smaller coils 120 in the heating chamber, the water drum be- 125

- ing so connected to the coils as to prevent accumulation of steam therein, and a pump for forcing fluid first through the preheating coils to the drum and from the drum through the header to the small coils in the heating chamber, and a steam drum connected to the outlet ends of the small coils.
3. In a steam generating apparatus, a combustion chamber, a bridge extending over the top from the front to nearly the back of the combustion chamber, a preheating zig-zag coil embedded in the bridge, a heating chamber above the combustion chamber, a preheating zig-zag coil in front of the heating chamber and extending from top to bottom of the heating chamber and in communication with the coil in the bridge, a series of smaller coils in the heating chamber, a water drum and a header interposed between the preheating coils and the smaller coils in the heating chamber, the water drum being so connected to the coils as to prevent accumulation of steam therein, and a pump for forcing fluid first through the preheating coils to the drum and from the drum through the header to the small coils in the heating chamber, and a steam drum connected to the outlet ends of the small coils with a pressure reducer between the small coils and the steam drum.
4. A steam generator comprising a flame chamber, preheating coils and coils with smaller diameter for exposing the fluid in small streams to the heat, a plurality of water drums between the preheating coils and smaller coils, said drums being normally in communication with the inlets only of the smaller coils, means for connecting the drums to the outlets of the smaller coils to allow circulation in either direction through the smaller coils and drums with means for forcing fluid in a single direction through said coils and drums.
5. A steam generator comprising a combustion chamber surrounded with comparatively large preheating coils, a heating chamber, a plurality of small heating coils extending vertically through the heating chamber, a plurality of water drums and a steam drum in the heating chamber above the small coils, the coils and drums being normally so connected that fluid may be forced once only in a single direction through the preheating coils, the drums and the heating coils, said steam drum connected to the ends of the heating coils and normally disconnected from the water drum with means to connect the steam drum and water drums to allow circulation in either direction through the system.
6. A steam generator comprising a combustion chamber surrounded with comparatively large preheating coils, a heating chamber, a bridge having a preheating coil embedded therein and extending between said chambers, a plurality of small heating coils extending vertically through the heating chamber, a plurality of water drums and a steam drum in the heating chamber above the small coils, the coils and drums being normally so connected that fluid may be forced once only in a single direction through the preheating coils, the drums and the heating coils, said steam drum connected to the ends of the heating coils and normally disconnected from the water drum with means to connect the steam drum and water drums to allow circulation in either direction through the system.

HENRY A. NICHOLSON.
